COLLATING RACK

Robert E. Ostwald, 112 Ramblewood Ave.,
Staten Island, N.Y.
Filed Jan. 13, 1960, Ser. No. 2,283
1 Claim. (Cl. 270—58)

This invention relates to a collating device and more particularly to an improved rack useful in the manual sorting and collating of stacks of paper sheets.

While there is a variety of mechanical collating devices whereby a plurality of sheets may be delivered from individual stacks to a sorting zone so that the sheets from each of the various stacks are positioned in any desired order, these devices are cumbersome, expensive, and not justified in an operation where it is only necessary to collate two stacks of sheets.

The present device represents an extremely efficient and expeditious aid in collating sheets from two stacks manually. The operator needs only one hand to manipulate the sheets from each stack, thus leaving the other hand free to place the pairs of sheets in any desired position, such as a third stack. This device so increases the speed of manual collation that with very little outlay for equipment, the speed of a mechanical collating machine can be equalled or surpassed.

A primary object of the invention, therefore, is to provide a unitary support and guide for two stacks of paper sheets and an intermediate tapering element which assists in separating individual sheets from the stack and permits the top sheet from each stack to be drawn upwardly and into face to face contact.

A further object of the invention is to provide a universal collating guide having an outwardly tapered base element for supporting two stacks of paper sheets and an integral upwardly extending tapered separator.

A further object of the invention is to provide a sheet collating guide having a pair of spaced, tapered sheet guides connected to a base member for biasing the edge of a stack of sheets on each side of the guide members.

Further objects will be apparent from the specification and drawings in which:

FIGURE 1 is a perspective showing my improved collating guide, and

FIGURE 2 is an end view of the structure of FIGURE 1 showing the manner in which the guide is manipulated.

The invention comprises essentially a base member having two outwardly tapered flanges or legs formed integrally with an elevated central portion tapering upwardly and having a lateral notch adjacent the mid point thereof. Desirably the base member may be provided with steps near the junction between the flanges and the vertical member to assist in separating the sheets from the stacks.

Referring now more particularly to the drawings, my improved collating guide comprises a base element 5, having two laterally extending flanges 6 and 7 which slope or taper outwardly towards their edges. The base 5 is formed integrally with two tapered guide elements 8 and 9 so that in end elevation guides 8 and 9 have triangular configurations which are arcuate at their apexes 10, 10. A notch 11 separates the two elements 8 and 9 adjacent the mid portion of the base 5 for a purpose to be described more fully hereinafter. If desired, a step 12 is formed on each side of elements 8 and 9 between the bottom of the elements and flanges 7. A similar step 13 is formed on the opposite side of elements 8 and 9.

In operation, a stack 15 of paper sheets is placed on foot 7 and on step 12 so that one edge of the stack fits snugly against the tapered lateral faces of elements 8 and 9. A second stack 16 of sheets is similarly positioned

2

on foot 6 so that the lateral edge of each stack is curved upwardly and so the edge of the stack is displaced from the vertical as seen clearly in FIGURE 2. The operator exerts a slight downward pressure on the edge of each stack as seen in FIGURE 2 by means of thumb and either forefinger or middle finger. Suitable rubber stalls 17 and 18 may be used by the operator if desired. With an upward contracting motion of the operator's fingers, the top sheet 19 and 20 from each stack is separated therefrom and simultaneously lifted in face to face relation as shown clearly in FIGURE 2 so that one sheet of each stack is quickly positioned against each other.

The steps 12 and 13 are of particular importance in creating an area into which the stack may be depressed to facilitate the separation of the top sheet only from each stack. The notch 11 is also important in that it permits fast and accurate collation by using the thumb and middle finger if it is difficult for a small handed operator to span the distance between the stacks. Furthermore, as the stacks become nearly exhausted, it is simple to stretch the fingers through the gap 11 rather than over the top of one of the elements 8 or 9.

The construction of my improved separator is universal insofar as the size of the sheets in each stack is concerned. The ability to quickly collate sheets of paper or folded material for insertion into envelopes is outstanding. The device is particularly adapted to the combining of original written material and copy paper in photo copy and white printing processes. Light, sensitive copy paper is placed face down on one side of the separator and the original copy face up on the opposite side. The operator can in one motion combine the original and the copy paper by picking them up together and in this position they are ready for use in the copying machine.

The invention is extremely simple, efficient and inexpensive. It may be cast, molded or formed out of a piece of any material. Where a relatively light substance is used, such as wood or a synthetic plastic, it is desirable to securely fasten the base to a solid object such as a table or a bench. If it is important that the device be portable, it may be cast out of a metal such as solid aluminum or brass. In this way there will be no tendency for the guide to be displaced on a table and thus destroy the connection between the edges of the stack and the guiding members 8 and 9.

Having thus described my invention, I claim:

A collating rack comprising a horizontally disposed base member having a planar surface tapering gradually upwardly from each opposite side edge thereof in the direction of one another, with each planar surface adapted to receive a stack of sheets in flat relation thereon, a vertically disposed web portion centrally positioned on said base, the opposed side surfaces of said web portion tapering downwardly and outwardly in the direction of the respective inclined planar surfaces of said base and adapted to receive the end edges of the respective stacked sheets placed thereagainst, a step portion uniting each inclined planar surface of said base member to the respective tapered surface of said web portion, each of said step portions raising the end of said stack of sheets adjacent each of the tapered surfaces of said web portion from said planar surfaces, and a notch portion centrally disposed in and extending laterally through said web portion.
